UNITED STATES PATENT OFFICE.

VINTSON G. PATTERSON, OF INDIANAPOLIS, INDIANA.

OIL BURNER.

Application filed March 4, 1924. Serial No. 696,744.

To all whom it may concern:

Be it known that I, VINTSON G. PATTERSON, a citizen of the United States, residing at Indianapolis, in the county of Marion and State of Indiana, have invented new and useful Improvements in Oil Burners, of which the following is a specification.

My invention has reference, in its broad aspect, to improvements in oil burners of the type wherein the oil is distributed in a thin film over an evaporating surface, and the vapor drawn down and mixed with air for combustion in a fire pan or tray. More particularly it is my purpose to provide an oil burner of this character, which will induce an exceedingly hot flame and eliminate the formation of carbon deposits.

In order to accomplish the foregoing and other equally important objects which will hereinafter appear, I have provided a hollow, semi-spherical, ribbed distributing member over which the oil film flows, and a hollow semi-spherical dome for confining the vapor emanating from the oil. The dome, however, serves a dual purpose in that it becomes intensely heated thereby completing vaporization of the oil, and it is formed with a lip which extends below the periphery of the first mentioned member to form a combustion chamber, and a guide for directing the flame in an unbroken circle in my fire pan or tray.

Another advantageous feature of my invention is the elimination of supplementary means for attaching the separate parts thereof. All of the parts of my burner are seated one upon the other and are held in position by their own weight so that they may be detached with ease for cleaning and the like, and are unlikely to become broken or deranged. Furthermore, my burner is formed without blind cavities or recesses which lend to the accumulation of carbon, and increase the cost of manufacture due to complication of the process of casting the parts.

To these and other ends, my oil burner consists in the construction, arrangement and combination of parts described herein-after, illustrated in the drawings, and pointed out in the claims forming a part of this specification.

One embodiment of my invention is repre-

sented by way of example in the accompanying drawings, wherein;

Figure 1 is a sectional side elevation of my oil burner,

Figure 2 is a top plan view of the assembly,

Figure 3 is a top plan view of the oil distributing member,

Figure 4 is a side view of the oil distributing member,

Figure 5 is a side view of my vaporizing dome, and

Figure 6 is a bottom plan view of my vaporizing dome.

Like characters of reference refer to like or similar parts throughout the several views of the drawings, in which;

The numeral (1) designates the fire pan or tray of my burner which is circular in configuration and substantially dish shaped with a uniformly curved bottom rising centrally to an up-struck portion (2) formed with a central opening (3). The peripheral edge surrounding the opening (3) is substantially flush with the top of the fire pan, and the fire pan is formed with an annular depending flange (4) constituting a base upon which the burner is designed to rest.

The fire pan or tray (1) is formed with a plurality of ribs (5), here shown as three in number, and each rib is stepped as shown in Figure 1 to receive and properly support the remaining major parts of my burner. Upon the intermediate steps (6) of the ribs (5) a semi-spherical, hollow, oil distributing member (7) is adapted to be supported, and upon the apex of the member (7) is formed a circular raised portion (8). Radiating from the raised portion (8) and terminating at the peripheral edge of the member (7) are a plurality of ribs (9) which are here shown as three in number, and formed beneath the raised portion (8) and depending interiorly of the member (7) is a boss (10) into which is adapted to extend an oil feed pipe shown in dotted lines at (11). The oil feed is of the gravity type, and the source of fuel supply is not here shown. Formed in the member (7) and communicating at an angle with the interior of the boss (10) are a plurality of openings (12) through which the oil is fed to the exterior surface of the member

(7) where it gradually distributes itself and flows downward toward the fire pan in a thin film.

In order to complete the vaporization of the oil and confine such vapors, I have provided a semi-spherical, hollow dome or cowl (13) which rests upon the ribs (9) of the member (7) and extends downwardly past the peripheral edge of said member to form a mixing chamber (A). The edge of the dome (13) is flared outwardly and curved upwardly to form a lip (14) which is supported on correspondingly formed steps of the ribs (5) of the fire pan. The lip is designed to direct the flame into the fire pan in an unbroken circle, and the dome (13) is highly heated by such flame thereby completing the vaporization of the oil without formation of carbon.

As shown in Figure 1, the feed pipe (11) is of less diameter than the opening (3) through which it extends, and consequently air is admitted to the interior of the member (7) whence it is drawn down between the fire pan up-struck portion (2) and the wall of the member (7) to the mixing chamber (A). As the suction force necessary to draw in the air is directly proportional to the intensity of the generated heat, the richness of the combustible mixture will be automatically regulated to insure the greatest intensity of heat with the consumption of the least amount of fuel.

In operation, the fuel is simply fed by gravity through the pipe (11) whence it passes through openings (12) and distributes itself upon the exterior surface of the member (7). The vapor is ignited as it passes the lip (14) of the dome (13) and as the dome becomes more intensely heated vaporization is increased to a point where the entire process is carried out most economically and without the formation of carbon deposits or the like. In assembling or dismounting the parts of my burner they are placed upon or lifted off the fire pan, there being no supplementary attaching means utilized. Furthermore it has been found in practice that my burner operates without noise, or the attendant roaring sound customary with this general type of burner.

While in the foregoing, there has been illustrated and described such combination

and arrangement of elements as constitute the preferred embodiment of my invention, it is nevertheless desired to emphasize the fact that interpretation of the invention should only be conclusive when made in the light of the subjoined claims.

Having described my invention, and its objects with such attention to detail as will thoroughly acquaint one skilled in the art with its construction and advantages, I claim—

1. An oil burner comprising a base provided with an opening and formed to provide a fire pan, a plurality of ribs formed on the base and radiating from a point adjacent the opening to the firepan, said ribs being provided with a plurality of steps, an oil distributing member seatable upon certain of the steps of the ribs of the base and provided with a boss above the opening in the base, said oil distributing member being formed with a plurality of ribs and openings between the ribs and communicating with the interior of the boss at an angle thereto, and a dome seatable upon the ribs of both the oil distributing member and the base.

2. An oil burner comprising a base provided with a central opening and formed to provide a uniformly curved firepan, a plurality of ribs formed on the base and radiating into the fire pan from a point adjacent to the opening in the fire pan, said ribs being formed with a plurality of steps, a semi-spherical oil distributing member seatable upon certain of the steps of the ribs of the base and provided with a boss, said oil distributing member being formed with a raised portion, and a plurality of ribs radiating from the raised portion with openings formed between the ribs and through the raised portion into communication with the interior of the boss at an angle thereto, a dome seatable upon the raised portion and upon the ribs of both the oil distributing member and the base, and a uniformly curved lip formed on the dome and seatable upon certain of the steps of the ribs of the base, said steps being curved to conform to the curvature of the lip.

In testimony whereof, I affix my signature hereunto.

VINTSON G. PATTERSON.
